UNITED STATES PATENT OFFICE.

GEORGE W. OAKES, OF CRYSTAL CITY, MISSOURI, ASSIGNEE TO PITTSBURGH PLATE GLASS COMPANY, A CORPORATION OF PENNSYLVANIA.

APPARATUS FOR APPLYING ABRASIVE TO PLATE GLASS GRINDING MECHANISM.

Application filed April 18, 1922. Serial No. 555,378.

The invention relates to an apparatus for handling, grading and applying abrasive material, such as sand to machines used in grinding plate glass. The objects of the invention are, (1) to improve the initial grinding operation so that a flat uniform surface is secured more quickly and danger of breakage reduced, (2) to reduce the wear upon the pump parts and those portions of the grader exposed to the action of the abrasive, (3) to avoid the danger of clogging the grader and still secure a thick mixture of the abrasive in the early stages of grinding and, (4) to permit the use of a grader of smaller size than would otherwise be possible.

Heretofore it has been customary to supply the new or green sand for each grinding operation to the sump and then pump the mixture up into the grader and supply it to the grinder in grades which are progressively finer as the grinding progresses. In following this procedure, difficulty is experienced in securing a sufficiently thick mixture for giving the best results in the initial grinding, and a certain amount of the worn sand is carried along with the new sharp sand thus interfering to a certain extent in this first rough grinding. The same result occurs where the new sand in measured amount is supplied directly to the grader at the beginning of the grinding operation instead of to the sump.

The practice has also been followed of supplying the new sand to a separate sump, and then pumping it to a supply hopper which discharges to the table as the grinding progresses until enough new sand is supplied for the grinding operation, after which the grinding is continued using the grading apparatus in the usual way. This procedure also has the disadvantage of supplying a mixture which is not sufficiently thick and involves the use of an extra pump and conduits incident to the circulation of the abrasive to the supply hopper.

In carrying out my process these difficulties are avoided by using a new sand hopper which discharges directly to the table and to which the new or green sand is supplied from above by means of a bucket or telfpher. An amount of sand is supplied to the hopper which is sufficient for the grinding operation before such operation starts. This sand is then washed to the table in a

very thick mixture and the rough grinding completed by the use of this mixture before the abrasive from the grader is brought into service for carrying out the finer grinding. The relatively thick mixture thus supplied cushions the runners and tends to prevent breakage, and because of the sharp quality of the new sand, the high spots on the table are rapidly cut away. The sharp, new sand is in this way brought into service immediately without passing through the grader and without imposing any wear on the pump or other grader parts, and none of the finer grades in the grader are disturbed or carried to the table prematurely. One embodiment of the invention is illustrated in the accompanying drawings where-

in:

Figure 1 is a side elevation of the apparatus which is preferably employed with certain of the parts thereof in sections, and Fig. 2 is a vertical section through the new sand hopper.

Referring first to the general arrangement of parts as shown in Fig. 1, 1 is a glass grinding table which may be of any approved type and driven in the usual manner; 2 is one of the runners such as is commonly employed in the grinding of plate glass; 3 is a trough lying beneath and encircling the outer edge of the grinding table and adapted to receive the water and abrasive from such table during the grinding operation; 4 is a sump or collecting receptacle into which the mixture of sand and water from the trough 3 runs by gravity; 5 is a grader into which the mixture of sand and water from the sump 4 is lifted by means of the pump 6 driven from the motor 7; 8 is a trough for conducting the mixture of sand and water from the grader to the grinding table; 9 is a new sand hopper provided with an outlet pipe 10 also leading to the grinding table and 11 is a bucket carried by an overhead crane, not shown, for delivering new sand to the hopper 9.

The grader 5 is preferably of the type shown in the Bechtel Patent #1,089,895, issued March 10, 1914, although some other type of grader might be substituted, if desired. This grader has an overflow pipe 12 through which any mud and sand too fine for use is carried to the sewer 13 or some other waste receptacle. The abrasive in the tank is graded by the upward flow of water

produced by the pump 6, the coarser grades lying at the bottom of the tank and the grades becoming finer and finer from the lower levels to the higher levels. The different grades are withdrawn through the pipes 14, 15 and 16, the finer grades being withdrawn through the pipe 16 which has its inner end in the form of a flexible tube adjustable vertically. Intermediate the ends 10 of the tank is an overflow 17 which discharges to the pipe 18 leading back to the trough or gutter 3. In operation those grades which are not being used are returned to the sump, this being accomplished by having those of the pipes 14, 15 and 16 which are not in use discharged to the box 19 and thence to the sump through the pipe 20. This particular grader constitutes no 15 part of the present invention and reference is made to the Bechtel patent heretofore referred to for a showing of the details of construction and the method of operation.

The construction of the sand hopper 9, to which the new or green sand is supplied, will 20 be seen by reference to Fig. 2 which shows the hopper in section. A screen 21 is provided at the bottom of the hopper and through this screen projects a washout pipe 22. This pipe is connected with a source 25 of water supply and has a plurality of upwardly directed discharge slots 23 which direct the water upwardly along the sides of the hopper. Farther down is another water pipe 24 which is directed downwardly 30 through the discharge pipe 10. The two pipes 22 and 24, together constitute an effective means for undermining and washing out the contents of the hopper.

The method of operation is as follows:— 35 A measured quantity of new sand sufficient to carry out the complete grinding operation is supplied to the hopper 9 by means of the bucket 11. The rotation of the grinding table now being started, a flow of water is admitted through the washout pipes 22 and 24 to carry the sand down through the pipe 10 onto the table, the runners at this time being raised slightly above the surface of the glass. Only sufficient water is supplied 40 through the pipes 22 and 24 to properly wash out the sand and give a relatively thick mixture. As soon as this mixture covers the surface of the glass on the table, the runners are gradually lowered, the layer of sand on the table acting as a cushion for the runners and tending to avoid the danger of breakage, such as sometimes occurs when the runners come too sharply in contact with the glass. The rough grinding action is 45 continued until the sand is exhausted from the hopper 9 and a fairly flat uniform surface is secured upon the glass. The time required for this action varies, but ordinarily runs from 10 to 15 minutes. During this time the sand is fed on continuously and

due to the sharp character of the sand the high spots are rapidly cut away and a flat surface secured.

During this application of the new sand for the rough grinding, the mixture of sand and water which is thrown from the table is collected in the sump 4 and pumped up into the grader 5 and separated into grades running from coarse to fine. At this time the grader will not only contain the sand 70 received from the table during the emptying of the hopper 9, but will also contain a considerable amount of sand in suspension remaining from preceding operations, so that after the conclusion of the rough grinding 75 there will be a collection in the grader of a sufficient quantity of the finer grades to finish the grinding operation. As soon as the tank 9 is emptied, the supplying of sand from the grader 5 to the table through the 80 trough 8 is started. The first grade is the coarsest from the pipe 14, after which finer and finer grades are supplied from the pipes 15 and 16 until the grinding with the sand is completed and the glass is ready for the 85 final smoothing operation with the emery which is applied in the usual way.

The application of the sand in the manner above set forth facilitates the speed of grinding as compared with the use of a grader, such as the grader 5 alone. This is due to the fact as heretofore referred to, that all of the sand supplied from the hopper 9 in the initial operation is sharp, new sand which has an effective cutting action and to the fact that the mixture supplied is thicker than any mixture which it is practicable to supply from the grader 5. If it were attempted to secure as thick a mixture 90 from the grader 5 alone for the coarse grinding, the grader would become clogged up and become ineffective to properly separate the grades. Furthermore, a large amount of the finer grades would be 95 entrapped with the coarse material and interfere with the cutting action of the coarse material when applied to the table. The thicker mixture as supplied from the tank 9 not only speeds up the grinding action as 100 compared with a thinner mixture, but also serves as a cushion in letting the runners down, permitting the lowering of the runners more quickly and with less care and reducing the danger of breakage. Since the 105 new sand applied from the hopper 9 to the table, in the first instance does not pass through the grader preliminary to its use, there is not the wear upon the grader and pump parts as would be the case if the new sand were supplied to the sump 4 and carried through the grader before its application to the table. This is an important feature in the upkeep of the grader since the abrasive rapidly wears out the piping and 110 pump parts, requiring frequent replace- 115

ments and since the action of the sharp, new sand is particularly damaging. The expedient also permits of the use of a smaller grader than if the tank 9 were not used, 5 since the work thrown upon the grader is much less, due to the fact that the coarse new sand does not have to be taken care of in the grader before its application to the grinder. A further advantage of the system resides in the fact that the system 10 adapts itself to the use of a measured quantity of sand for each side ground, which quantity is very easily and conveniently measured out and supplied by means of the 15 telpher bucket. Other advantages incident to the method and apparatus will be readily apparent to those skilled in the art.

What I claim is:

1. The method of applying sand to a 20 grinding machine which consists in collecting a measured quantity of new abrasive in a solid mass in a supply hopper located above the machine, washing such abrasive directly to the table in an ungraded condition 25 by supplying water thereto sufficient to

provide a relatively thick mixture, rough grinding with such mixture, collecting the abrasive and water from the machine and supplying them to a grader, and thereafter regrading and reusing the abrasive. 30

2. In combination in grinding apparatus, a grinding machine including a table, a supply hopper above the machine having an outlet leading directly to the table, a carrier for supplying abrasive from above in a solid mass to said hopper, water supplying means for undermining and washing the abrasive from the hopper to the table in a relatively thick mixture, a grader also located above the machine having outlet 35 means leading to the table, a sump in which the mixture of abrasive and water from the table is collected, and elevating means for supplying the mixture in the sump to the 40 grader. 45

In testimony whereof, I have hereunto subscribed my name this 15th day of April, 1922.

GEORGE W. OAKES.
